Merrill E. Clark

UNITED STATES PATENT OFFICE.

EDMUND WEIGELE, OF BERGENFIELD, NEW JERSEY, ASSIGNOR TO G. & G. ATLAS SYSTEMS, INC., OF NEW YORK, N. Y., A CORPORATION OF NEW YORK.

CARRIER FOR PNEUMATIC-TUBE SYSTEMS.

Application filed May 11, 1926. Serial No. 108,243.

This invention relates to carriers for pneumatic tube systems, and particularly to carriers which are intended for use in connection with credit sales in department stores and the like. It is understood, however, that the invention is not limited to any particular use that may be made of the novel carrier.

When carriers are employed in connection with credit sales it is ordinarily their function to carry a memorandum of the sale or the proposed sale, to an "authorizer" who verifies the purchaser's account. In a large store there are usually a number of authorizers, each one of whom has in her charge the lists of credit customers covering names beginning with certain letters of the alphabet. For example, one authorizer may have the lists of names beginning with the letters A, B, C, another with the letters D, E, F, etc. When these carriers with their contents are received at the main authorizer's desk it is necessary for her to open them and inspect the contents in order to determine to which authorizer it should go for verification. This, of course, consumes considerable time and effort. The object of my invention is to provide a carrier intended primarily for credit use, which embodies means enabling one to determine from looking at its exterior and without opening it, the initial of the name of the customer which appears on the credit slip contained in it. The manner in which I accomplish this object and the numerous advantages of my invention will be set forth more fully hereinafter.

In the drawing, Fig. 1 represents in diagrammatic fashion, a typical tube room installation in so far as it relates to the handling of credit slips; Fig. 2 is a side elevation of my improved carrier, showing the means for identifying the initial of the name on the slip within; Fig. 3 is a view of the same carrier partly in section, taken at a different angle; Fig. 4 is a transverse sectional view of my improved carrier taken on the line 4-4 of Fig. 3, the carrier being closed as shown in these figures; Fig. 5 is a transverse sectional view similar to Fig. 4 but showing the carrier open; and Fig. 6 is a view similar to Fig. 2 but showing the carrier in which the initial identifying means are of a slightly different character.

55 In the Canton Patent No. 1,505,542, Aug.

19, 1924, there is disclosed a carrier intended for use in connection with credit sales as distinguished from cash sales, and for that purpose provided on the exterior with projecting protuberances so that the person picking it up will know without looking at it that it is a credit carrier and not a cash carrier. My invention may, if desired, be applied to such a carrier, although, because of the difference in appearance and in outer contour inherent in my improved carrier, I do not think it necessary to employ protuberances, such as shown in the Canton patent.

Referring to Fig. 1 of the drawing, A indicates the delivery station where the carriers from the sales clerks are received in the tube room. These carriers may be either cash or credit. The person (or persons) on duty at this delivery station distributes the cash carriers in any convenient manner to the operators who make change and dispatch the credit carriers over to the credit authorizer's station B. This may be done by means of a pneumatic tube as indicated in the drawing, or by a belt, or in any other desired manner. The person in charge of the main authorizer's station then distributes the carriers received there to the individual authorizers in accordance with the initial of the customer's name. The individual authorizers, after verifying the account, then return the carriers to the main authorizer's desk, whence they are sent back to the dispatcher's desk C. From here they are dispatched back to the sales clerks who sent them.

It is obvious that if the person in charge of the main authorizer's desk B is compelled to open each carrier in order to determine the initial of the customer's name, the transactions are considerably delayed. As I have said, I provide means by the use of which the customer's initial can be ascertained without opening the carrier or disturbing its contents in any way. I shall now proceed to describe my carrier.

As is well known, carriers of the character in which I am interested ordinarily comprise two cylindrical shells, such as indicated in the drawing at 11, 12, one of which is within the other. These two shells may be rotated relatively, and to facilitate the rotation one of the end flanges, as for example 13, is secured to the outer shell 11 and 110

- the other one 14 to the inner shell 12. Each of these shells has an oblong opening in it, the opening in the shell 11 being designated in the drawing by the number 15 and the one in the inner shell by the number 16. To open the carrier for the insertion or removal of the contents the two shells are moved relatively until the two openings 15, 16, are in register, as indicated for example 10 in Fig. 5. To close the carrier the shells are rotated relatively until the two openings are entirely out of register, as shown for example in Fig. 4 and also in Figs. 2, 3 and 6.
- 15 The carrier so far described is the usual form of carrier. In applying my invention to this carrier I, in effect, flatten down a portion of that part of the inner shell 12 which is exposed through the opening 15 in 20 the outer shell when the carrier is closed. The result is as shown, for example, in Fig. 4, where this part of the inner shell is represented in cross section by a chord 17 instead of an arc. For convenience I shall call the 25 flat part 17 of the inner shell a chordal plate. Upon this chordal plate I mount some suitable form of initial designator. As shown in Figs. 2-5 this consists of a disk 18 which is rotatable but normally held in position by 30 some such means as the spring 19, and a pointer 20 which is affixed to the plate 17. The disk 18 is preferably divided up into the desired number of sectors and upon all the various sectors are placed initials corresponding to the lists of the several authorizers. In addition to providing each sector with initials I also preferably color each one with a distinguishing color. For example, 35 the A, B, C sector may be red, the D, E, F sector yellow, etc. The purpose of employing the colors in addition to the initials is that to some operators the colors may provide a more rapid means of distinguishing than the letters.
- 40 45 The carrier of Fig. 6 is similar to the carrier above described except that the letters and colors appear on the chordal plate 17 instead of on the disk 18, and the pointer 20 appears on the disk instead of on the plate.
- 50 The intended method of use of this carrier is as follows: The sales clerk who is making a credit sale picks up one of these credit carriers and after opening it to the 55 position of Fig. 5 inserts into it the credit slip. She then closes the carrier to the position shown in Fig. 4 and having noted the name of the customer adjusts the disk 18 to conform to the initial of the customer's name. She then dispatches the carrier to the 60 tube room where in turn it is sent to the main authorizer's desk. The operator there, without opening it, determines from looking at the disk to which of the individual authorizers it should go and immediately de-

livers it to that authorizer. From this point on the carrier is treated in the manner usual for credit carriers.

As appears from the above description the means which I have provided for informing the main authorizer of the initial of the customer are simple to construct and positive in operation. By being placed on a chordal plate they are protected against all injury which might occur from the usual treatment accorded to devices of this kind. Also, they add greatly to the efficiency of handling credit slips.

My invention is not limited to the particular forms of designating disk illustrated in the drawing, but is intended to cover the use of any initial designating means located on a chordal plate formed on the inner shell of the carrier.

The terms and expressions which I have employed are used as terms of description and not of limitation, and I have no intention, in the use of such terms and description, of excluding any equivalent of the features shown and described, or portions thereof, but recognize that various modifications are possible within the scope of the invention claimed.

What I claim is:

1. A carrier for pneumatic tube systems comprising an outer cylindrical shell and an inner cylindrical shell, each provided with an opening therethrough, said shells being rotatable relatively to each other for moving said openings into and out of register to open and close said carrier, said inner shell being provided with an indicator adjustable to different positions to give different indications and so located as to be exposed through the opening in the outer shell when said carrier is closed.

2. A carrier for pneumatic tube systems, comprising an outer cylindrical shell and an inner cylindrical shell, each provided with an opening therethrough, said shells being rotatable relatively to each other for moving said openings into and out of register to open and close said carrier, said inner shell being provided with adjustable indicating means, so located as to be exposed through the opening in the outer shell when said carrier is closed, said indicating means including a dial upon which is marked indicating symbols, and a pointer cooperating with said dial and movable relatively thereto.

3. A carrier for pneumatic tube systems comprising an outer cylindrical shell and an inner cylindrical shell, each provided with an opening therethrough, said shells being rotatable relatively to each other for moving said openings into and out of register to open and close said carrier, said inner shell being provided with adjustable indicating means, so located as to be exposed

through the opening in the outer shell when said carrier is closed, said indicating means including a dial marked in different colors, and a pointer cooperating with said dial and 5 movable relatively thereto.

4. A carrier for pneumatic tube systems comprising an outer cylindrical shell and an inner cylindrical shell, each provided with an opening therethrough, said shells

being rotatable relatively to each other for 10 moving said openings into and out of register to open and close said carrier, said inner shell being provided with a chordal plate so located as to be exposed through the opening in the outer shell when said carrier is 15 closed, said chordal plate being provided with adjustable indicating means.

EDMUND WEIGELE.
